Primary Examiner — Austin Murphy(74) *Attorney, Agent, or Firm* — Anova Law Group, PLLC(57) **CLAIM**

A new, original, ornamental design for cases for portable computers, as shown and described.

DESCRIPTION

FIG. 1 is a perspective view of cases for portable computers showing my new design;

FIG. 2 is a use state view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines in the drawing depict environmental subject matter only and form no part of the claimed design.
